CLAIM

The ornamental design for a cart for storing dishes or the like, as shown and described.

DESCRIPTION

FIG. 1 is a perspective view of a cart for storing dishes
or the like showing our new design;

FIG. 2 is a front perspective view thereof, all other side perspective views being identical thereto;

FIG. 3 is a top perspective view thereof;

FIG. 4 is a bottom perspective view thereof;

FIG. 5 is a perspective view of a modified form of FIG.
1;

FIG. 6 is a right side perspective view of FIG. 5, the left side perspective view being identical thereto;

FIG. 7 is a front perspective view of FIG. 5, the rear
perspective view being identical thereto;

FIG. 8 is a top perspective view of FIG. 5; and

FIG. 9 is a bottom perspective view of FIG. 5.
